UNITED STATES PATENT OFFICE.

FRANK L. WAASER, OF GLENBROOK, CONNECTICUT.

DESIGN FOR A COMBINATION INKSTAND AND DESK-SUPPLIES HOLDER.

Application filed November 22, 1921. Serial No. 517,118. Term of patent 7 years.

To all whom it may concern:

Be it known that I, FRANK L. WAASER, a citizen of the United States, residing at Glenbrook, in the county of Fairfield, State of Connecticut, have invented a new, original, and ornamental Design for Combination Inkstand and Desk-Supplies Holder, of which the following is a specification, reference being had to the accompanying sheet of drawing, forming a part thereof.

The drawing is a perspective view of a combination inkstand and desk supplies holder embodying my new design.

I claim:

The ornamental design for a combination inkstand and desk supplies holder substantially as shown.

FRANK L. WAASER.
